UNITED STATES PATENT OFFICE.

JOSEPH T. BAILEY, OF PHILADELPHIA, PENNSYLVANIA.

DESIGN FOR A JEWELRY-RING.

51,311.

Specification for Design.

Patented Oct. 2, 1917.

Application filed August 15, 1917. Serial No. 186,431. Term of patent 14 years.

To all whom it may concern:

Be it known that I, JOSEPH T. BAILEY, a citizen of the United States, residing in the city and county of Philadelphia, State of Pennsylvania, have invented a new, original, and ornamental Design for Jewelry-Rings, of which the following is a specification, reference being had to the accompanying drawing, forming part thereof.

Figure 1 is a plan view of a jewelry ring showing my new design.

Fig. 2 is a side elevation thereof.

Fig. 3 is a side elevation at a right angle to Fig. 2.

I claim:—

The ornamental design for a jewelry ring, as shown.

JOSEPH T. BAILEY.
